[57] CLAIM

The ornamental design for an ornament or plate display holder, as shown and described.

DESCRIPTION

FIG. 1 is a perspective view of an ornament or plate display holder showing my new design;
FIG. 2 is a front elevational view thereof;
FIG. 3 is a top plan view thereof;
FIG. 4 is a right side elevational view thereof, the left side being a mirror image of that shown;
FIG. 5 is a rear elevational view thereof;
FIG. 6 is a perspective view of an alternate embodiment thereof;
FIG. 7 is a front elevational view of the embodiment of FIG. 6;
FIG. 8 is a top plan view of the embodiment of FIG. 6;
FIG. 9 is a right side elevational view of the embodiment of FIG. 6, the left side being a mirror image of that shown; and
FIG. 10 is a rear elevational view of the embodiment of FIG. 6.
